CLAIM

The ornamental design for a finial, as shown and described.

DESCRIPTION

FIG. 1 is a front and side perspective view of a finial showing my new design;

FIG. 2 is a front view thereof, the rear view being a mirror image;

FIG. 3 is a left side view thereof;

FIG. 4 is a right side view thereof;

FIG. 5 is a top view thereof;

FIG. 6 is a bottom plan view thereof; and,

FIG. 7 is a rear and side perspective view of my design. The dashed lines in FIGS. 1 and 7 are shown for environmental purposes only and form no part of the claimed design. The dotted lines shown in FIGS. 1, 3, and 7 represent peripheries of the claimed design and form no part thereof.
